CLAIM

We claim the ornamental design for a display stand, as shown and described.

DESCRIPTION

FIG. 1 is a perspective view of a display stand according to our invention;

FIG. 2 is a front view of the display stand shown in FIG. 1; FIG. 3 is a rear view of the display stand shown in FIG. 1; FIG. 4 is a left side view of the display stand shown in FIG. 1;

FIG. 5 is right side view of the display stand shown in FIG. 1;

FIG. 6 is a top plan view of the display stand shown in FIG. 1;

FIG. 7 is a bottom plan view of the display stand shown in FIG. 1;

FIG. 8 is a perspective view of a display stand according to a second embodiment of our invention;

FIG. 9 is a front view of the display stand shown in FIG. 8; FIG. 10 is a rear plan view of the display stand shown in FIG. 8;

FIG. 11 is a left side view of the display stand shown in FIG. 8;

FIG. 12 is right side view of the display stand shown in FIG. 8;

FIG. 13 is a top plan view of the display stand shown in FIG. 8; and,

FIG. 14 is a bottom plan view of the display stand shown in FIG. 8.

The broken lines depict portions of the display stand that form no part of the claimed design.

1 Claim, 14 Drawing Sheets
